RICHARD M. CRAIG, OF SAN ANTONIO, TEXAS

RADIO RECORDING MEANS

Application filed September 5, 1929, Serial No. 390,638.

This invention has for its object the provision of means whereby a selection heard through a radio-receiving set may be recorded as it is received and the record played back through the receiver as often as desired. The invention provides means whereby, if so desired, the record may be erased or nullified and a different selection recorded on the same record member, although a plurality of record blanks may be provided and the records made thereon stored for future use at such intervals as may meet wishes or taste of the owner. It frequently happens that radio listeners are attracted or specially entertained by some musical selection or some remarks that are being received through the radio set and have a desire to hear such selection or remarks repeated, and the present invention provides means for supplying such want. Many radio-receiving sets at the present time are built into cabinets which contain a phonograph attachment whereby phonograph records may be played and heard through the instrumentality of a magnetic pick-up device which converts the sound waves of the record into electric pulsations which are sent into the radio amplifier and there reconverted into sound, and this invention is especially adapted to such instruments. The invention is illustrated in the accompanying drawings and will be herein-after fully set forth.

In the drawings:

Figure 1 is a plan view of a cabinet having a pick-up device whereby phonograph records may be played through a radio amplifier, the top of the cabinet being removed and the recording device of the present invention being illustrated.

Fig. 2 is a vertical section on the line 2—2 of Fig. 1 with the recording mechanism in elevation,

Fig. 3 is a sectional elevation on the line 3—3 of Fig. 1,

Fig. 4 is an enlarged detail section of the magnetic recording stylus, and

Fig. 5 is a diagram showing the circuits through which the record is made and then replayed through the pick-up device.

In the drawings, the reference numeral 1 indicates a cabinet which may be of any of the forms now on the market, this cabinet containing a horizontal shelf or partition 2 above which is a turntable 3 and below which is a motor (not shown) whereby the turntable may be rotated. The turntable is secured concentrically upon the upper end of a vertical shaft 4 which is journaled in and extends through the shelf 2 and is driven directly by the motor. Upon this shaft above the shelf is a beveled pinion 5 which meshes with a similar pinion 6 on the inner end of a threaded shaft 7, as shown most clearly in Fig. 2. The shaft 7 is journaled in bearings 8 provided therefor at the ends of a bracket 9 which is disposed in radial relation to the shaft 4 and is provided at its inner end with a hub or sleeve 10 loosely encircling the shaft 4 below the pinion 5 whereby the bracket 9 and the shaft 7 may have a pivotal movement about the shaft 4. Pivoted upon the shelf 2 at the rear of the turntable is a post 11 having a forked upper end and in the forked upper end of said post is pivoted an angle lever 12 having one arm extending forwardly to a point above the threaded shaft 7, as shown at 13, and equipped at the end of said arm 13 with a nut 14 resting on and meshing with the threads of the shaft 7. An intermediate portion of the lever 12 rises from the fulcrum of the lever to a point above the plane of the turntable and then extends forwardly over the turntable, as shown at 15. Pivoted to the end of the arm 15 of the lever 12 is a carrier arm 16 to the free end of which is secured a magnetic coil 17 having a soft iron core 18 disposed centrally therein and extending below the coil, the lower end of the core being tapered, as shown at 19, to constitute

80

a recording stylus. When this recording mechanism is to be used, a thin steel disk 20, preferably of the same diameter as the turntable, is placed upon the turntable and the 5 point of the stylus 19 rests on said plate. Upon referring to Fig. 1, it will be noted that the recording instrumentality is disposed at one side of a diameter of the turntable and cabinet and at the opposite side of said diameter is located the pick-up device 21 which is 10 ordinarily employed for electrically playing the phonograph records.

Referring to Fig. 5 of the drawings, a radio 15 amplifier 22 is indicated conventionally and at 23 is conventionally illustrated the loud speaker which is electrically connected with the amplifier. Wires 24 are tapped into the wires connecting the loud speaker with the amplifier and these wires are carried into the 20 winding of the magnet 17, as shown in Fig. 5, a switch 25 being interposed in the wires 24 so that the circuit may be broken or closed at will. At the detector side of the receiving set, wires 26 are connected thereto and these wires lead to the phonograph pick-up 25 device, as indicated at 27, while branches 28 extend to a point adjacent the switch 25 whereby they may be coupled to the magnet 17 when the recorded selection is to be played. At 29 is indicated a battery and at 30 is a switch whereby the circuit of said battery may be opened or closed. This battery is connected into the coil of the magnet 17 and the switch 30 is normally open.

When it is desired to record a selection by the use of my device, the pick-up arm 21 is pushed to one side, as shown in Fig. 1, and the steel disk 30 is substituted for any record which may happen to be upon the turntable 35 or if no record is on the turntable then, of course, the steel disk is simply placed upon the table. The turntable is preferably of wood or fiber and is generally covered with felt so that it will be non-magnetic and will not interfere with the magnetism of the disk. The switch 25 is closed so as to connect the 40 magnet 17 with the amplifying side of the radio receiver and, consequently, the core 18 of the magnet will be magnetized and, as it is resting upon the disk 20, magnetism will be 45 imparted to the disk, as will be understood. The turntable is set in motion as the recording operation starts and the magnetic stylus will, consequently, travel over the table in a spiral path corresponding to the spiral path of sound records made upon the ordinary phonograph disk, and the pivotal mounting of the arm 9 permits it to conform to the varying angular position of the 50 recorder and the nut 14 which connects the recording bracket or lever with the threaded shaft. The rotation of the turntable and the 55 shaft carrying the same is transmitted through the pinions 5 and 6 to the threaded shaft 7 which, in turn, causes travel of the

nut 14 and thereby swings the angle lever 12 and the recording stylus carried thereby about the supporting post 11 as a center in an obvious manner. The impulses passing over the wires 24 will obviously vary in 70 strength in exact consonance or sympathy with the impulses passing to the loud speaker, and these impulses, flowing through the coil 17, will magnetize the core 18 to a greater or less degree and, consequently, will 75 vary the intensity of the magnetism induced in the steel disk by the soft iron core 18. The disk, being steel, will retain its magnetism so as to constitute a record. When the selection has been recorded, the switch 25 is opened 80 and the lever 12 is rocked about its fulcrum so that the magnet will be raised from the record and the nut 14 will be raised from the threaded shaft 7. The magnet and the nut are then swung to the point at which the making of the record was begun and then reengaged with the record disk and the threaded shaft respectively. The switch 25 is then thrown over so that the wires 28 will 85 be connected with the coil, and if the turntable be then again rotated, the record will be reproduced through the radio detector and amplifier. In reproducing, the steel disk functions as a permanent magnet inducing magnetism of varying strength in the core 18 which sets up corresponding currents 90 in the coil 17. These currents are carried to the radio detector and amplifier, issuing from the loud speaker as sound waves.

When it is desired to erase the record, the 100 switch 25 is set in a neutral open position and the switch 30 is closed thereby sending a direct even current through the coil 17 and, consequently, equalizing the magnetism in the disk so that the variations which constitute the magnetic record will no longer 105 exist.

My recording attachment is very simple in its construction and operation and may be 110 very easily applied to existing instruments without involving heavy expense. I have been able with the use of a steel disk having a diameter the same as an ordinary phonograph turntable to record matter about one and one-half times as long as the matter recorded upon an ordinary phonograph record disk.

It will, of course, be understood that when the pick-up arm 21 is to be used the lever 15 and the parts carried thereby are swung to 120 one side out of the way and vice versa.

Having thus described the invention, I claim:

An attachment for radio-receiving sets comprising a turntable to carry a disk, an 125 angle lever mounted at the rear of the turntable and having one arm extending over the turntable and another arm extending under the turntable, a stylus carried by the free end of the lever to rest on a disk carried 130

by the turntable, a threaded shaft below the turntable, a nut carried by the lever under the turntable and engaged with said threaded shaft, means for rotating the turntable,
5 means for rotating the threaded shaft in consonance with the turntable, and means for pivotally shifting the shaft about the center of the turntable as the turntable and shaft rotate.

10 In testimony whereof I affix my signature.
RICHARD M. CRAIG. [L.S.]
